COMBINATION DRAINER AND HOLDER HAVING
DUAL ATTACHING ELEMENTS OR SIMILAR
ARTICLE

Thomas P. O'Donnell, 220 Highland Blvd.,
Forest Hills, N.Y.

Filed Aug. 20, 1962, Ser. No. 71,346

Term of patent 14 years

(Cl. D9—2)

Fig. 1.

Fig. 2.

Fig. 3.

FIGURE 1 is a top plan view of a combination drainer and holder having dual attaching elements or similar article showing my new design;

FIGURE 2 is a side elevational view thereof; and

FIGURE 3 is a fragmentary top perspective view thereof.

I claim:

The ornamental design for a combination drainer and holder having dual attaching elements or similar article, substantially as shown.
